UNITED STATES PATENT OFFICE.

FRANK H. CAVEN, PHILADELPHIA, PENNSYLVANIA.

DESIGN FOR FRINGE.

SPECIFICATION forming part of Design No. 23,000, dated January 2, 1894.

Application filed September 22, 1893. Serial No. 486,227. Term of patent 3½ years.

To all whom it may concern:

Be it known that I, FRANK H. CAVEN, a citizen of the United States, residing at Philadelphia, Pennsylvania, have invented a certain 5 Design for Fringe, of which the following is a specification.

My design for fringe is clearly illustrated in the accompanying drawing.

D is the heading and d , d' , d^2 , d^3 and d^4 are bands connected to the heading by strands e , e' , e^2 , e^3 and e^4 . The bands d , d^2 and d^3 are narrow bands, while the bands d' and d^4 are wide bands, being in the present instance the same width as the heading D.

5 The strands connecting the several bands are arranged in two sets, one set inclining toward the right and the other inclining toward

the left, one alternating with the other and giving the effect as shown in the drawing, and depending from the band d^4 is a fringe f , and upon the band d' are rosettes E, although these rosettes may be dispensed with in some instances without destroying the general features of the design.

I claim—

The design for the fringe described and illustrated in the accompanying drawing.

In testimony whereof I have signed my name to this specification in the presence of two subscribing witnesses.

FRANK H. CAVEN.
